UNITED STATES PATENT OFFICE.

HARRY S. REED, OF EAST LANSING, AND RALPH D. LAMIE, OF LANSING, MICHIGAN.

PROCESS FOR DISTILLING SHALE.

Application filed October 16, 1925. Serial No. 62,855.

The objects of this invention are:

First, to provide an improved method for distilling shale which is rapid and highly efficient.

5 Second, to provide an improved method for distilling which is continuous in operation, the walls of the retort being automatically kept free from accumulations.

Third, to provide an improved method for 10 distilling shale in which the highly volatile and more valuable liquid by-products are distilled and saved with the least possible decomposition, thereby obtaining such products in their most valuable form.

15 Objects pertaining to details and economies of construction and operation will appear from the detailed description to follow. The invention is defined in the claims.

A structure which is a preferred means 20 for carrying out the method is illustrated more or less diagrammatically in the accompanying drawing, forming a part of this application, in which:

Fig. 1 is a general assembly view, the off- 25 take being on reduced scale, a part being a vertical longitudinal section through the apparatus, taken on line 1—1 of Figs. 2 and 3, and the retort being in full lines with part of its shell broken away, the chimney structure being sectioned in part on line 13—13 of Fig. 12. The air forcing means is shown diagrammatically.

Fig. 2 is a vertical cross section taken on line 2—2 of Figs. 1, 12 and 13, showing details of the furnace.

Fig. 3 is an elevation end view from the driving end of the retort, the relation of the combustion chamber and flue being indicated by dotted lines.

40 Fig. 4 is an enlarged longitudinal sectional view of the retort taken on irregular line 1—1 of Figs. 2 and 3 and on line 4—4 of Figs. 5, 6, 7, 8 and 11, the feed screws appearing in full lines.

45 Fig. 5 is a cross section of the retort taken on line 5—5 of Fig. 4, showing the discharge dippers and structure.

Fig. 6 is a cross section taken on line 6—6 of Fig. 4, showing the scalloped retaining 50 plate at the discharge end of the retort.

Fig. 7 is a cross section taken on line 7—7 of Fig. 4, showing the partition retaining and grading plate within the body of the retort.

55 Fig. 8 is a cross section taken on line 8—8 of Fig. 4, showing the feed screws.

Fig. 9 is a perspective view of the angular tumbling, grinding, scraping elements, of tetrahedral and different angular forms.

Fig. 10 is a perspective view of the ball 60 tumbling milling elements.

Fig. 11 is a detail cross section taken on line 11—11 of Fig. 1, showing the adjustable supporting rollers for the revolving retort.

Fig. 12 is a detail plan view looking down 65 on the top of the stack, air forcing means being omitted.

Fig. 13 is a detail vertical sectional view taken on line 13—13 of Fig. 12, showing details of the flue structure and hot air supply 70 to the furnace burners, air pressure omitted.

Fig. 14 is a detail section taken on line 14—14 of Figs. 1 and 4, showing details of the flushing pipe for steam or gas and the connections to the powdered fuel discharge device.

In the drawings similar reference numerals identify similar parts throughout the views.

1 is the brick work of the furnace, which is 80 provided with the usual fire brick lining. 2 is the chimney structure. 3 is a burner for the furnace. 4 is the combustion chamber or fire box. 5 is the heating chamber for heating the retort. 6 is the direct flue from this chamber. 7 is the auxiliary indirect flue for directing heat to the preheater. 8 is the cylindrical retort. 9 is the preheater in the form of a feed conduit trough, with conveyor screw 91. 10 is the bunker or hopper for supplying and feeding the shale. 11 is the telescopic feed connection to the feed means 12. 13 is the discharge for the residue from the retort 8. 14 is the adjustable roller support. 15 is the driving gear for the retort. 16 is a 95 steam supply. 17 is the vapor and gas outlet for the distilled material from the retort.

The furnace 1 may be heated in any suitable way, but gas for the furnace is especially available, it being produced as a product of distillation. This is supplied to the burner through pipe 185 from the storage tank or gas holder 184. The gas burners deliver into the combustion chamber and entrain hot air from the down air flue from the chimney which is under pressure as well. This heated air and products of combustion are circulated in chamber 5 around the retort 8 and then pass through flue 6 to the chimney. A portion of it is by-passed through the auxiliary flue 7. The direct flue 6 is controlled by the damper 61 and the flue 7 is controlled by 100 105 110

the damper 71, and thus by regulating the dampers 61 and 71 the extent of the heating of the preheater 9 is controlled.

10 is the hopper for the shale which is to be distilled. This hopper delivers into the U-shaped trough 9 of the preheater which, as stated, is provided with a feed screw 91 which is driven by the pulley or gear 92 and carries the shale through the preheater trough, 10 dropping it through the telescopic pipe 11 into the multiple screw feeder 12, which is composed of a large outer tubular shell 121 in the bottom of which is a propeller feed screw 122. A pair of small semicircular troughs 15 of different lengths are disposed above the feed screw 122, the shorter one 123 containing the feed screw 124 and the longer one 125 containing the feed screw 126. These details are seen in Figs. 4 and 8. These feed screws 20 are actuated by a suitable gear train 127 of any convenient design, and they may be actuated separately or geared together in any suitable and well-known way. This feed is made integral with the gas delivery 17 and in 25 central spaced relation therefrom. The multiple screws and feed troughs of different length deliver the shale evenly and distribute it in the retort so that the heat is readily maintained and the material is quickly and 30 evenly heated.

The retort 8 is made of steel boiler plate preferably, and cylindrical in form. It is supported on pairs of adjustable supporting rollers by which the relative elevation of the 35 ends and the inclination may be controlled by suitable adjusting screw 142 of usual construction. The opposite ends of the retort are provided with projecting tires 141 which rest on the rollers for controlling and permitting the rotation of the same. An annular gear 15 is provided at the discharge end of 40 the retort, adapted to be driven by any suitable power means, not necessary to be shown. These parts are all standard commercial devices.

45 A residue discharge 13 for the retort is tubular in form and contains a screw conveyor 131 driven by a suitable gear or pulley 132 and delivers into the vertical telescopic discharge pipe 134 which is controlled by a star valve 135 which maintains a gas tight connection at that point. The discharge 13 is provided with a suitable stuffing box connection to the head 81 of the retort 8. A pipe 50 16 is provided to deliver steam or fixed gas into the retort at the driven and discharge end.

The gas-off-take 17, as before indicated, is 55 tubular in form and connected by stuffing box 171 to the head 82 of the retort 8. This gas discharge connects to the telescopic gas off-take 18 which delivers to condensers 181 and scrubbers 182. The suction pump 183 draws off the product, as indicated, and dis- 60 charges the non-condensable gas into the

holder or gas tank 184, where it is available for use. A part is delivered through pipe 185 to the furnace for fuel, as before indicated.

The smoke and products of combustion pass up the smoke flue 21. The down air 70 flues 22 are disposed each side thereof and are separated by comparatively thin walls of fire brick 23. The heated air is delivered downwardly by the blow fan 221 through header 222 and air connections 223 to the combustion 75 burners and is entrained by the burners and passes on to the combustion chamber for heating the retort (see Figs. 2 and 13).

The retort 8 is divided by partitions 83, 83 and 84, into distilling chambers 85, 86 and 87 80 and discharge chamber 88. The partitions 83 are scalloped around the edges at 831 and contain a series of radial slots 832 of appropriate size to retain the milling and tumbling elements in each chamber and provide a passage to the next succeeding chamber to permit the shale which is being distilled to pass freely on. Fine particles pass ordinarily through the scallops 831. The partition 84 is not perforated and is scalloped at 841 and 90 permits the discharge of the thoroughly pulverized residue from the shale into the discharge chamber 88.

Within the discharge chamber 88 and connected to the walls thereof are a series of 95 buckets 881 which are disposed radially and are adapted to convey the residue from the shale upwardly and discharge it into the fixed hopper 136 which delivers into the discharge conduit 13, where the feed screw 131 100 discharges the same, as indicated.

In the first or main distilling chamber 85 we supply milling and scraping elements of heat conducting material, preferably chilled cast iron, which are angular in form, as indicated in Fig. 9, some having square ends and some shown tetrahedral. It is only necessary that these elements have one flat side and a scraping edge. In the first chamber some of these irregular elements are three 110 inches and some six inches in diameter or cross section in their shortest diameter. With these we provide a quantity of balls or round elements (see Fig. 10), the exact spherical form not being essential, from three to six inches in diameter to assist in the flow or tumbling of the angular scraping milling elements so that they will scrape the sides of the retort and free it of any accumulation due to the fluxing of the shale that is being distilled. Also, the angular scraping elements serve to clean the balls and the balls react so that the milling elements are all kept clean, while at the same time scraping and cleaning the retort.

115 The shale is thus broken up as soon as it is fluxed in the process of distilling and the reduced pieces passed to the second compartment 86. The sticky condition of the distilling mass is overcome in the first chamber. 120

In the second compartment the pieces are further considerably reduced in size and similar milling and scraping elements are made use of, from one and one-half to two 5 inches in diameter, with preferably a somewhat increased proportion of balls. These further pulverize the material, break up the surfaces and expose the same to the heating elements and the heated walls of the retort. 10 The material is still further reduced and passed in the smaller size to the third distilling chamber 87 where the tumbling and scraping elements are one and one-half inches in diameter and the final milling of the material is accomplished, where it is reduced to 15 a powder and the residue delivered out to the discharge chamber 88 and carried away, as indicated.

The pipe 16 delivers steam or fixed gas 20 axially through the stuffing box 161 through the hollow shaft of the screw feed 131 into the third distilling chamber 87, steam being preferred. The volume of steam delivered at this point quickly carries along with it all 25 of the distilled products and carries them off through the gas discharge 17 to the gas off-take pipe 18, as before indicated. Because of the passage of this steam the distillate is not unduly heated and is passed off before it 30 is injured, and the cracking of any of the products of distillation is thus reduced.

Having described the complete apparatus, we will indicate its course of operation. The shale in the hopper 10 drops into the pre-heater 9 where it is carried forward by the feed screw 91, thence through the feed pipe 11 to the multiple feed screw 12 where it is delivered into the first compartment 85 of the retort 8. The retort is heated on all sides 35 by the products of combustion circulating around the same, as indicated, and the heating of the preheater is controlled by adjustment of the dampers 61 and 71, as pointed out.

45 Shale is distributed in the retort chamber 85 by the three feed screws 122, 123 and 125, as indicated. In this retort are the tumbling, milling and scraping bodies, about half of which are round and from three to six inches 50 in diameter, and the remainder are of angular scraper form, as illustrated in Fig. 9. As the retort is slowly revolved and is adjusted to the proper inclination for the particular grade or kind of shale, the shale advances in 55 the same and is heated by these milling and scraping bodies and by the heated walls of the retort. The shale quickly fluxes and this tends to adhere to the walls of the retort or to the heating bodies, but this is prevented by 60 the angular elements because the motion imparted to these bodies by the rotation of the retort is less than the speed of either the periphery of the retort or the round milling bodies. Hence they act as scraping devices 65 and keep the walls of the retort and the sur-

face of the round milling elements and themselves free from any hard carbonaceous deposit which would insulate or cut down the free heat transfer of these elements coating with each other and the surface of the retort. Further, by reason of these angular elements, an irregular snake-like movement is imparted to the whole mass within the retort, thereby assisting in scraping the inner walls of the retort and advancing the charge 70 through the chamber. The entire mass is broken and then dried out and becomes more or less like coke in character, and passes readily through the first partition 83 to the second distilling chamber 86. There the milling 75 elements are of the same character but of smaller size. They act upon the shale to reduce it to smaller dimensions and it is still further distilled and thence passed to the third and last distilling chamber 87, where 80 the milling elements are comparatively small and of the same character, the proportion of the balls being increased. The entire residue of the shale is here ground to a fine powder and delivered to the discharge chamber 88. 85 All of the recoverable volatiles have thus been distilled off.

The vapors that are developed by the heat would soon be cracked and injured if allowed to remain in the hot retort. They are carried away by a current of steam coming through the pipe 16 in a small volume which is super-heated and expanded. The steam circulates freely through the retort and takes up any of the vapors and passes them along through the outlet 17 to the gas take-off 18. There they pass to the condensers 181 and scrubbers 182. Where the shale oil formed during the distillation is condensed and recovered in the usual way, the vapors formed during distillation and passing through pipe 18 are drawn through the condensing and scrubbing system by gas pump 183. The non-condensable gases are passed through the gas pump and stored in tank 184 under pressure. This 110 non-condensable gas is readily available for use in the furnace, which uses a part of the same to maintain the required temperature. There is still an amount of gas that is available for general use for various purposes, as 115 in internal combustion engines or gas furnaces. All of the volatile products have been recovered by this method, in their most valuable form.

The heat is very much conserved by our 120 improved apparatus. As soon as it has done its work of distillation, it is passed to the up-take flue where it heats the air in the down air flues which deliver this heated air to the burners and furnace to help maintain combustion. The heat contained in the air is 125 thereby conserved. A considerable amount of the volatiles of the shale would be recovered readily in a single retort, like the compartment 85, but by providing the same in 130

steps and reducing the size of the milling elements, it is found that substantially all of the volatile content will be recoverable, and by making use of the usual condensers and 5 scrubbers the same is made available, either as liquid or gaseous products of the various forms derivable from the particular shale being distilled.

By dividing the retort into separate compartments the mass of milling and scraping elements can be disposed throughout the length of the retort as necessary for greatest efficiency. For example, the plastic state of the shale during distillation occurs in the 10 first chamber, therefore a greater heat transfer and milling and scraping action are necessary, and so in this chamber we introduce a greater weight of larger milling and scraping elements.

20 By subjecting the mass undergoing distillation to successive steps in reduction and grading, we insure a thorough reduction and removal of all the volatiles.

Having thus described our invention, what 25 we claim as new and desire to secure by Letters Patent is:

1. The continuous process of distilling oil shale in an externally heated sealed tumbling barrel ball mill retort, subdivided by foraminous partitions into several different ball mill chambers, each succeeding partition having progressively smaller openings, each succeeding chamber containing progressively smaller angular grinding elements and ball grinding 30 elements of heat conducting material, and of a size to be retained by each said foraminous partition, consisting in, reducing the shale to a lumpy condition, preheating the oil shale lump, then introducing the pre-heated oil 35 shale in the lump form into the ball mill chamber containing the largest grinding elements, heating the shale until fluxing begins, and grinding the fluxed portion away, screening the ground mass to the next adjoining ball mill chamber, repeating these steps of 40 heating, grinding, and screening until the spent shale is reduced to a powder and simultaneously flushing the distilled products from the retort, with steam to carry away the volatile 45 products of distillation.

2. The continuous process of distilling oil shale in an externally heated sealed tumbling barrel ball mill retort subdivided by foraminous partitions into several different ball mill 50 chambers, and each succeeding partition having progressively smaller openings, each succeeding chamber containing progressively smaller angular grinding elements and ball 55 grinding elements of heat conducting material, and of a size to be retained by each said foraminous partition consisting in reducing the oil shale to a lumpy condition, pre-heating the oil shale lumps, then introducing the pre-

heated oil shale in the form of lumps into the ball mill chamber containing the largest 60 grinding elements, heating the shale until fluxing begins, and grinding the fluxed portion away, screening the ground mass to the next adjoining ball mill chamber, repeating these steps of heating, grinding and screening until the spent shale is reduced to a powder and simultaneously flushing the distilled products from the retort with a gaseous medium inert to the distilled products to carry away the volatile products of distillation. 70

3. The continuous process of distilling oil shale in an externally heated sealed tumbling barrel ball mill retort subdivided by foraminous partitions into several different ball mill chambers, and each succeeding partition having progressively smaller openings, each succeeding chamber containing progressively smaller angular grinding elements and ball grinding elements of heat conducting material, and of a size to be retained by each said foraminous partition consisting in reducing the oil shale to a lumpy condition, then introducing the oil shale in the form of lumps into the ball mill chamber containing the largest 80 grinding elements, heating the shale until fluxing begins, and grinding the fluxed portion away, screening the ground mass to the next adjoining ball mill chamber, repeating these steps of heating, grinding and screening until the spent shale is reduced to a powder and simultaneously flushing the distilled products from the retort with a gaseous medium inert to the distilled products to carry away the volatile products of distillation. 90

4. The continuous process of distilling oil bearing shale in an externally heated sealed tumbling barrel ball mill retort containing angular grinding elements and ball grinding elements of heat conducting material admixed in proportion to insure the flowing 100 tumbling action of such grinding elements consisting in, continuously introducing and subjecting shale in a lumpy condition to the simultaneous tumbling action resulting from the rotation of said retort and the grinding 105 action of the ball and angular elements to progressively heat the said shale lumps until fluxing begins at the surface, grinding away the fluxed part and repeating the operation on the residuary lumps until the volatiles are 110 distilled away and the spent shale is reduced to a powder and discharged and simultaneously flushing the distilled products from the retort with a gaseous medium inert to the 115 distilled products to carry away the volatile products of distillation.

In witness whereof we have hereunto set our hands.

HARRY S. REED.
RALPH D. LAMIE.
